UNITED STATES PATENT OFFICE

2,552,067

HYDRAULIC CONTROL SYSTEM

Thomas F. Stacy, Piqua, Ohio, assignor to The French Oil Mill Machinery Company, Piqua, Ohio

Application December 29, 1944, Serial No. 570,276

17 Claims. (Cl. 60—52)

1

This invention relates to a hydraulic motor device and especially to the controls of the motor.

An object of the invention is to provide an improved and simple control for hydraulic circuits by which a double acting hydraulic motor is operated.

Another object of the invention is to provide an improved control for a double acting hydraulic motor, with which packing friction opposing the advance of the working member may be reduced without interfering with the operations of the working member, with which the advantages of high pressure in the retracting chamber during the final increment of advance of the working member may be obtained with a minimum of packing friction on the working member, with which this result may be obtained automatically, and which will be relatively simple, practical and inexpensive.

Another object of the invention is to provide an improved control for a hydraulic motor by which the main control valve may be operated in a simple manner by power, and with which the pressure that may be maintained by the pump may be varied selectively between predetermined high and low pressures.

Various other objects and advantages will be apparent from the following description of one embodiment of the invention, and the novel features will be particularly pointed out hereinafter in connection with the appended claims.

In the accompanying drawings:

Fig. 1 is a schematic plan and elevation, with some of the parts in section, of a hydraulic motor and control circuits constructed in accordance with this invention, the controls being in the positions occupied when the motor is in normal, idle position, and the working member is retracted;

Fig. 1a is a schematic diagram of a part of Fig. 1 showing a slight modification of the controls;

Fig. 2 is a schematic diagram similar to Fig. 1 and illustrating the action of the various valves while the motor is advancing at rapid closing speed;

Fig. 3 is a view similar to Fig. 2, but representing a further period in the advance of the working member of the motor after the speed of the motor has been decreased to what is commonly called the working speed;

Fig. 4 is a view similar to Fig. 3, but representing the parts in the positions occupied during a gassing movement; and

Fig. 5 is a view similar to Fig. 4, but illustrating the operation of this hydraulic circuit during a return or retraction movement of the working member.

In the illustrated embodiment of the inven-

2

tion, and referring particularly to Fig. 1, the hydraulic motor includes a cylinder 1 having an open end through which a piston or working member 2 extends, with the usual packing 3 provided between the shank of this working member or piston 2 and the wall of the chamber of the cylinder 1, adjacent to the open end of the cylinder. This packing 3 is commonly placed under pressure or firm contact with the piston by an adjustable gland 4 as usual in hydraulic motors. This motor is shown as having a rapid advance chamber 5, and a high pressure advancing chamber 6, and for this purpose the inner end wall of the cylinder 1 has a tubular wall 7 which extends towards the open end of the cylinder. The piston or working member 2 has a recess 8 opening from its inner end face, which telescopes loosely over the tubular wall 7 so that the working member or piston 2 has a central post or ram 9 which extends inside the tubular wall 7 and terminates at its inner end in a head 10 which carries piston rings or packing fitting the inner surface of the wall 7.

The outer periphery of the working member or piston 2, at its inner end, terminates in a head 11 which fits and slides along the inner periphery of the cylinder 1. This head 11 may, and preferably does have one or more piston rings 12 in its periphery to provide a seal between the high pressure chamber 6 and the retracting chamber 13 surrounding the working member or piston 2 at the opposite side of the head 11 from the high pressure chamber 6. While these piston rings 12 may be of any suitable packing material, they are preferably split, metal, resilient rings similar to the split, metal piston rings commonly employed on the pistons of internal combustion engines and steam engines.

The high pressure chamber 6 is provided with a prefill opening 13 leading to the reservoir, shown only diagrammatically by the reference 14, it being understood that the closed end of cylinder 1 is usually disposed in the reservoir to simplify the connections and to allow any leakage to pass directly into the reservoir. Such an arrangement is well known in the art, and therefore it has not been illustrated. This passage 13 is normally controlled by a prefill valve element 15 which has an operating stem 16 extending outside of the passage 13 into a position to be engaged and operated by a prefill pilot piston stem 17 which operates in a direction endwise of stem 16 in a pilot chamber 18. A spring 19 acting between a shoulder on the stem 16 and a portion of the housing of the cylinder 1 through which the stem 16 passes, yieldingly urges the valve element 15 into its closed position, and a spring 20 surrounding the pilot stem 17, and compressed

against an annular disc 20a and a piston head 20b on the stem 17 urges that stem in a retracted direction or a direction away from the end of the stem 16.

Fluid under pressure for the operation of the motor is obtained from a suitable pump 21 which is driven continuously by a motor, not shown, or any other suitable source of power, and it is of the type known as a variable delivery pump with a compensator 22 thereon by which the maximum pressure to be developed by the pump may be automatically controlled. The intake side or port of the pump is connected by a pipe 23 to the reservoir 14, and the output side or port of the pump is connected to a pipe 24 having in series therein a pressure relief valve 25 which operates, if a safe operating pressure is exceeded, to connect the pipe 24 to an exhaust pipe 26 leading to the reservoir, so that a dangerously high operating pressure for the pump will be avoided. The pipe 24 has a branch 27 leading directly to the retracting chamber 13, and another branch 28 leading to a main control valve 29.

This control valve has a port 30 opening into a pipe 31 which leads to the cylinder 1, and pipe 31 has one branch 32 leading to the rapid traverse advancing chamber 5, and another branch 33 leading to the high pressure advancing chamber 6. In series in the branch 32 are two check valves connected in parallel to one another. One of these check valves 34 is an ordinary free check valve which passes fluid from the pipe 31 to the chamber 5, and closes automatically to prevent reverse flow, and the other valve 35 is a pressure relief valve which opens to connect the rapid traverse chamber 5 to the pipe 31 and allow escape of fluid from the chamber 5 only in excess of a selected pressure for which the valve 35 is set. In other words, the check valve 34 passes fluid freely from the pipe 31 into the chamber 5 while valve 35 is set to maintain a desired back pressure in the chamber 5 during the period when fluid is being expelled from chamber 5. These pressure relief valves 35 are well known and available in the open market, and one type of such valve is shown, by way of example, in U. S. Patent No. 2,043,453.

The other branch 33 of pipe 31 also has a valve 36 in series therein. This valve 36, when in one position, passes fluid from the pipe 31 into the chamber 6 and vice versa, and when in its other position it interrupts fluid flow through the branch 33. The valve element 37 of valve 36 is operated by a pilot chamber 38, in one direction or into one position in which it opens the branch 33 for fluid flow therethrough, and a similar, but smaller pilot chamber 39 at the opposite end of valve 36 serves to cause movement of the valve element 37 into a position in which it interrupts fluid flow from the branch 33. A pipe 40 connects the pilot chamber 39 to the portion of the pipe 33 which is connected directly to the pipe 31. The pilot chamber 38 is connected by a pipe 41 to a valve 42 having a connection 43 to the reservoir and a pipe 44 leading to the pipe 27.

When the valve element 45 of the valve 42 is in one position, such as shown in Fig. 1, the pipe 41 is connected to the pipe 43 and disconnected from the pipe 44. If the valve element 45 is moved into its other position, which would be downwardly in Fig. 1, a land on that valve element would move between the connections to the pipes 41 and 43 so as to disconnect the pipe 41 from the pipe 43, and another land on the valve ele-

ment would move out of blocking relation to the port opening into the pipe 44, which would connect the pipe 41, through the valve, to the pipe 44. This valve 42 may be herein later referred to as a pilot control valve, as will appear from the function which will be described later. The valve element 45 has an outwardly extending stem 46 which is connected by a loose connection 47 to one end of a lever 48 pivoted at 49. The other end of the lever 48 has a fork 50.

The working member 2 carries a rod 51 extending in the direction of travel of the member 2, and having a collar 52 threaded in a direction lengthwise thereon for adjustment into different positions along its length. As the working member 2 advances, the collar 52 will engage in the fork 50 and rock the lever 48 from the position shown in Fig. 1 to the position shown in Figs. 3 and 4, which moves the valve element 45 from the position in which it connects the pipes 41 and 43 as shown in Fig. 1 to a position in which it breaks that connection and connects the pipe 41 to the pipe 44, as shown in Figs. 3 and 4. When the member 2 returns, the collar 52 which has been able to pass beyond the fork 50 during the advance movement, will again engage the fork and rock the lever 48 back into the position shown in Fig. 1, and then pass on downwardly beyond the fork, as shown in Fig. 1. By this arrangement, the valve 42 will be operated automatically by the advance and retraction of the working member, as will be later explained.

The main control valve 29 has a valve element 53 which moves endwise therein and has an operating stem 54 extending exteriorly thereof in a direction cross wise of the cylinder 1, as shown in Fig. 1. The valve element 53 is of the balanced type, with spaced lands 55 and 56 which fit the chamber in the valve along which they move. One land 55, has a length or width in the direction of movement of the valve element sufficient to cover and close the port 30 of the pipe 31 when the valve element is in the normal idle position shown in Fig. 1. Another land 56 is narrower or shorter in the same direction so that when the valve element 55 is in the position shown in Fig. 1, with the land 55 crossing the port 30, the port 57 opening into a pipe 58 leading to the pilot chamber 18 of the pre-filled valve will be uncovered, and fluid may pass from the pipe 28 into the valve chamber, around the edges of the land 56 and to a port 59 opening into a pipe 60 leading to the reservoir. The valve element 55 occupies an intermediate position in its endwise movement when in the position shown in Fig. 1, and when moved in either direction from that intermediate position, the land 56 will prevent movement of fluid around its edges. This type of valve is well known in the art and its details need not be further described.

Connected in series in the pipe 27 is an auxiliary valve 61 having a valve element 62, a pilot operating chamber 63 at one end of the valve element and a pilot operating chamber 64 at the opposite end of the valve element. The valve element is of the balanced type with spaced lands, and when the valve element is moved in one direction, it connects the retracting chamber 13 to a pipe 65 leading to the reservoir, and when in its other position, which is shown in full lines in Fig. 1, it connects the retracting chamber 13 directly to the pump. The pilot operating chamber 63 is connected by a pipe 66 to the pipe 31 leaving the main control valve 29, and the pilot operating chamber 64 is connected

by a pipe 67 to the pipe 44 leaving the valve 42. When advancing pressure is applied to the advancing chamber of the motor, this pressure in the pipe 34 will be transmitted to the pilot operating chamber 63 to operate the valve element 62 upwardly in Fig. 1 into a position in which the land 68 is disposed between the port openings into the sections of the pipe 27, and another land 69 uncovers the port into the pipe 65 that leads to the reservoir. Thus the valve 61 serves to connect the retracting chamber 13 alternately to the reservoir and to the pump depending upon the position of the valve element 68.

The pilot operating chamber 64 is larger in cross-sectional area than that of the chamber 63 so that even though both chambers 63 and 64 are connected at the same time to the pump pressure, the pressure in the chamber 64 will, because of its greater area, cause movement of the valve element 62 into the full line position in Fig. 1 which connects the retracting chamber to the pump. Within the pilot operating chamber 64 is a helical compression spring 70 which is compressed between the end of the valve element 62 and the end of the pilot chamber into which the pipe 67 opens, so that when pressure in the pipe 66 falls or is released, the spring 70 will shift the valve element 62 into the full line position shown in Fig. 1 and hold it there.

The outer free end of the stem 54 of the main control valve 29 carries a head 71 which slides in a passage 72 in a small housing 73. The head 71 abuts against a piston 74 also carried in a housing 73 for limited endwise movement in the same direction as the head 71, and this piston 74, at its other end, abuts against a flexible impermeous and imperforate diaphragm 75 which is clamped across a cavity or chamber 76 provided in the housing 73, and into which the piston 74 extends. The chamber 76, at the side of the diaphragm opposite from the piston 74 communicates with a pipe 77 leading to a 3-way valve 78 having a rotor which may be rocked by a handle 79 between two positions. A passage 80 in the rotor connects the pipe 77 to an exhaust pipe 81 when in one position as shown in Fig. 1, and to a pipe 82 leading to a source 83 of air under pressure when in its other position. The pipe 82 has a control valve 84 therein.

A lever 85 is pivoted at 86 on a suitable part of the cylinder or press frame, and one arm is forked to straddle the valve stem 54 in an annular groove 87, so that by rocking the lever 85 manually, the valve stem 54 may be shifted in either direction.

A bell crank lever 88 has one end forked to straddle a reduced shank 89 on the rod 51, so as to engage beneath a shoulder 90 on the rod 51. The lever 88 is pivoted at 91 on a bracket carried by the cylinder 4, and its other arm is also forked to straddle the valve stem 54 in an annular groove 92. When the working member 2 descends, it will, as it approaches its downward or fully retracted position, engage with the bell crank lever 88 and rock it in a direction to move the valve stem 54 to the right in Fig. 1 and place the valve element 53 in the intermediate, idle position shown in full lines in Fig. 1. A collar 93 is fixed on the valve stem 54, and a helical spring 94 surrounding the stem 54 abuts at one end against the collar 93 and at its other end against a sleeve 95 which is slidably mounted on the valve stem 54.

A link 96 is pivoted at 97 to the sleeve 95, and at its other end is pivoted at 98 to a link 99, which is pivoted at 100 to a bracket 101 on the press frame or cylinder 4. The link 96 may have a

handle 102 thereon by which the links 96 and 99 may be moved into or slightly beyond a dead center position as shown in Fig. 1 which is a toggle connection. By rocking the handle 102 to the left in Fig. 1, the links 96 and 99 may be moved out of a dead center position, during which the sleeve 95 will slide along the stem 54 to release the pressure on the spring 94. One may then, by manipulation of the lever 85 operate the valve element 53 of the valve 29 into any of the different positions so as to have complete manual control of the motor. When the handle 102 is moved back into the vertical position shown, the sleeve 95 moves to the left in Fig. 1, and places the spring 94 under compression so stem 54 is then responsive to the automatic controls.

The pump 24 of the type shown may have a pilot piston 103 in a pilot chamber 104 which may be supplied with operating fluid under pressure by a pipe 105 which is connected through a valve 106 to a branch pipe 107 leading through the pipe 44 to the pipe section 27 which connects the auxiliary valve 61 to the pump. The valve 106 may have its valve element 108 operated in one direction by a solenoid 109 and in the other direction by a compressed spring 110. When the valve element 108 is in the position shown in Fig. 1, into which it has been moved by the spring 110, it connects the pipe 105 to an exhaust pipe 111 leading to the reservoir. When the solenoid 109 is energized from any suitable manual or automatic control, the valve element 108 will be moved downwardly in Fig. 1 to compress the spring 110, and the valve element will then disconnect the pipe 105 from the pipe 111 and, instead, connect it to a branch 107 of the pipe 44. When the solenoid 109 is energized, and the pipe 105 is connected to the pipe 107, the pump pressure will be applied to the pilot chamber 104 to operate the piston 103, which has a limited movement, and limit the stroke of the pump and decrease the rate of delivery by the pump, so that the speed of operation of the press may be decreased while solenoid 109 is energized. This can be made effective for a breathing operation or for an initial opening movement of the press after the cycle is completed.

In Fig. 1a is illustrated a slight modification of the construction of Fig. 1, in which the rod 46 which is connected to the valve element 45 of the pilot control valve 42, instead of being connected to the lever 48 for operation by the working member, is provided with a piston head 112 which reciprocates in a cylinder 113. A compression spring 114 in the opposite end of the cylinder 113 urges the valve element 45 into the position shown in full lines in Fig. 1a. When pressure is applied to the upper end of the cylinder 113, it pulls the valve rod 46 downwardly in the same manner that the lever 48 moves the valve rod 46 downwardly in Fig. 1. The upper end of the cylinder 113 is connected by a pipe 115 to the pipe 66 which leads to the pilot chamber 63, and pipe 115 has, in series therein, a pair of valves 116 and 117 which are connected in parallel to each other, but as a group are in series in the pipe 115. The valve 116 is a free check valve which passes fluid in the direction of the arrow or away from the cylinder 113 and closes automatically to prevent reverse flow therethrough. The valve 117 is a suitable pressure relief valve which prevents flow therethrough in a direction away from the cylinder 113 but which opens automatically to pass fluid from pipe 66 to the cylinder 113, whenever

the pressure in the pipe 66 exceeds a selected pressure for which the valve 117 is set.

In the operation of a hydraulic motor with the controls in the positions shown in Fig. 1, the motor is idle with the working member in retracted position. The pump is delivering fluid into the pipe 24 which passes through the pipe 28, valve 29, around the land 56 to the exhaust pipe 60 leading to the reservoir. The arrows in Fig. 1 show the direction of travel of this fluid. The land 56 also uncovers the opening to pipe 58, so that the prefill valve element 15 may be closed. It will be noted that when the working member 2 approached its lowermost or retracted position, the shoulder 90 on the rod 51 engaged and rocked the bell crank 88 to shift the valve stem 54 to the right, into the position shown in full lines in Fig. 1, during which movement the spring 94 was compressed further.

If one wishes to cause a slight advance of the working member 2, the manual lever 85 may be rocked counter-clockwise in Fig. 1 to shift the valve stem 54 further to the right in Fig. 1, which causes the land 55 to uncover the port 30 and the land 56 to move between the opening into pipe 28 and the groove or port 57. This will cause the fluid from the pump to pass into the pipe 31 and then through one section of the branch pipe 32, free check valve 34 and the other section of branch pipe 32 into the rapid closure chamber 5. Pressure will also pass through pipe 40 to pilot chamber 39 and move valve element 37 upwardly in Fig. 1 to disconnect pipe sections 33.

The working member will then advance, but as soon as the lever 85 is released, the spring 94 will return the valve stem 54 and lever 85 to the position shown in Fig. 1, with the bell crank lever 88 engaging against the shoulder 90 if the movement of the working member is very slight. Usually for this purpose, however, the handle 102 is swung to the left in Fig. 1, so as to break the toggle connection formed by the links 96 and 99, which releases the pressure on the spring 94. The valve stem 54 will then remain in the positions into which it is moved and will have complete manual control of the movements of the working member 2. When the automatic controls are to be used, the links 96 and 99 are in the dead center position shown in Fig. 1, and to start an operation, the attendant operates the handle 79 of the 3-way valve 78, which connects the source of air under pressure to the chamber 76 at one side of the diaphragm.

The air pressure forces the diaphragm to the right from the position shown in Fig. 1, which moves the valve stem 54 to the right until the land 55 in valve 29 uncovers the port 30, as just explained. Fig. 2 shows the circuit arrangement at this time, and in Figs. 2 to 5 the parts have the same references, but the parts are shown in the different positions occupied in a cycle of movement. With the valve element 53 in the right-hand position from that shown in Fig. 1, and referring to Fig. 2, the pump delivers fluid under pressure through the pipe 24, pipe 28, valve 29, pipe 31, pipe section 32, the check valve 34, and pipe section 32 to the rapid closing chamber, which causes an advance of the working member 2. The pressure in the pipe 31 also is communicated through the pipe 66 to the pilot chamber 63, which operates the valve 61 to connect the pipe section 27 leaving the retracting chamber, to the exhaust pipe 65 running to the reservoir.

The working member moves upwardly rapidly, and since advancing chambers 5 and 6 are dis-

connected at valve 36, the suction in the high pressure chamber 6 causes the prefill valve 15 to open and allow fluid to pass from the reservoir directly into the high pressure chamber 6 to occupy the space created by the advance of the working member. As the working member advances, fluid is displaced from the retracting chamber 13 which passes directly to the reservoir through pipe 65 so that there will be no back pressure in the retraction chamber that would urge the packing 3 surrounding the piston part of the working member against the piston, with the result that the frictional resistance of the packing 3 on the piston is a minimum.

When the working member reaches the position in its advance where one desires to have a slower advance of the working member, but at a higher pressure, the collar 52, which has previously been suitably adjusted on the rod 51 will, at this time, engage in the fork 50 and rock lever 48 clockwise in Fig. 1 into the position shown in Fig. 3, which moves the valve element in the valve 42 into a position to connect the pipes 41 and 44 so that some of the fluid delivered by the pump into the pipe 44 may now pass through the pipe 44 and valve 42 into the pipe 67 leading to the pilot chamber 64. This causes the auxiliary valve 61 to connect the retracting chamber 13 directly to the pump 21, so that as the working member 2 continues to move upwardly or advance, the liquid displaced from the retracting chamber, instead of passing through the valve 61 to the reservoir as it did during the previous part of the advance of the working member, will now all pass through the valve 29 with the liquid delivered by the pump, and then will pass through the pipe 31 to the rapid closing chamber.

At the same time that pump fluid is delivered into the pipe 67 by the operation of the valve 42, some of the fluid passed by the valve 42 will also pass through pipe 41 to the pilot chamber 38 of the valve 36 to connect the pipe sections 33 to thus connect pipe 31 also to the high pressure chamber 6. This condition of the valve 36 is shown in Fig. 1, and the direction of flow is shown by the arrow at the valve 36 in Fig. 3. The fluid delivered by the pump will then be distributed between the two chambers 5 and 6, and this will break the suction in the chamber 6 so that the prefill valve 15 will be closed by its spring 19. The working member will then be advanced at a slower speed, but with a higher possible pressure throughout the remainder of its movement.

When the working member has completed its movement and one desires its retraction, the valve 79 is operated to connect the pipe 77 to exhaust, and disconnect it from the source of air under pressure. The spring 94 then shifts valve stem 54 in a direction toward the left in Fig. 1, so as to place the land 56 between the connection to the pipe 60 and the groove or port 57, and the land 55 between the port 30 and the opening into the pipe 28. The pump pressure will then be applied by pipe 58 to the pilot chamber 18, tending to open the prefill valve 15, but until the pressure in chamber 6 falls sufficiently, this valve 15 will not open. The fluid from the pump is delivered to the retracting chamber 13 instead of into the pipe 31 as shown by the arrow a in Fig. 4, and since the land 55 moved to the left of the port 30 in Fig. 1, the port 30 is in communication with an exhaust pipe 30a thus releasing pressure in the pipe 31.

Fluid from the chamber 6 can escape through the pipe 33, valve 36, pipe 31 and valve 29 to the reservoir, and the fluid pressure in the retracting chamber causes a retraction of the working member. The pressure relief valve 35 controls the escape of fluid from the advance chamber 5 so that the retraction of the working member 2 will not be too rapid, especially at the beginning. If full return movement is desired, this action will continue, but if the retraction of the working member 2 is desired only momentarily to release the pressure in the molds, so that gas in the molds can escape, then as soon as the desired small amount of retraction has occurred, the 3-way valve handle 79 is returned to its former position to have the diaphragm 75 force the valve stem 54 to the right, so as to reconnect the pump to the advancing chambers and a readvance of the working member then follows.

This will continue until the operator again moves the valve handle 79 to cause another retraction of the working member 2. The working member will then begin another return movement which, unless stopped by operation of valve 78 to cause a re-advance, will continue as shown in Fig. 5, the fluid flow being in the direction shown by the arrows *a* and *b* in Fig. 5. When the working member 2 reaches the same position in the return stroke at which, during its advance movement, it engaged the fork 50, the collar 52 will again engage the fork 50 and rock the lever 48 back into the position shown in Fig. 1. The collar 52 then continues its downward movement as shown in Fig. 5, and when substantially full retraction has occurred, the shoulder 99 engages and rocks bell crank lever 88 to move the valve stem 54 to the right and set the main control valve element 53 in the idle position shown in Fig. 1.

During the retraction of the member 2, as soon as the pressure in the high pressure chamber 6 fell, due to the release of fluid therefrom through the pipe 33, the pressure in the pipe 58 was able to open the valve 15 so that some of the fluid in the chamber 6 could escape directly through the prefill valve back into the reservoir. This greatly speeds up the retraction. When the main control valve 29 is returned to the condition shown in Fig. 1, the pressure in the pipe 58 is released, and valve 15 closes. When the valve 42 is returned to the Fig. 1 position during the return of the member 2, the pipe 67 is vented through the valve 42, so that pressure in the pilot chamber 54 is released. The spring 70, however, keeps the auxiliary valve element 62 in the position as in Fig. 1 because, at this time, the pressure in the pipe 66 is released at the main control valve 29. At the same time that the pipe 67 was vented, the pipe 41 was also vented which released the pressure in pilot chamber 38 of valve 36.

When the valve stem 54 is moved to the right to start an advance of the working member 2, the application of pressure to the pipe 31 will place fluid under pressure in the branch pipe 40 leading to the pilot chamber 39, which moves the valve element 37 upwardly in Fig. 1 to disconnect the pipe sections 33. The pilot chamber 38 is larger than chamber 39, so that even though pressure continues in the chamber 39, the application of the same pressure per unit area from the pump to the chamber 38 will cause an operation of the valve element 37 into the position shown in Fig. 1. Similarly, since the pilot

chamber 64 is larger than 63, the admission of the same pump pressure per unit area into both chambers 63 and 64, will result in the movement of the valve element 62 into the position shown in Fig. 1. The pressure in the pilot chamber 63 alone, however, when pilot chamber 64 is vented, will be sufficient to overcome the spring 70. The solenoid 109 is either manually controlled or controlled by any automatic mechanism, so that delivery of the pump can be changed during movement of the working member 2 when desired conditions have arisen. The manner of control of solenoid 109 is not a part of the invention sought to be covered in this application.

In the modification shown in Fig. 1a, the operation will be the same as explained for Fig. 1, except that the working member will not move the valve 42. When the pressure in the pipe 66, which will be substantially the same as that in the rapid closing chamber 55, exceeds a predetermined, selected pressure due to the working member encountering sufficient resistance, such as caused by engagement with the work, the pressure in the pipe 66 will rise as the pump continues to deliver fluid into pipe 31. This will cause the pressure relief valve 117 to open to pass the pump pressure to the chamber 113, with resulting compression of the spring 114 and operation of the valve 42 to connect the pump pressure through the pipe 67 to the pilot chamber 64 and to the pilot chamber 38.

A movement of the auxiliary valve 61 to connect the retracting chamber directly to the pump for the same purpose as explained in connection with Fig. 1, then occurs, and at the same time the valve 36 will connect the pump to the high pressure chamber, so that the member 2 may move forwardly at a slower rate, but at the higher possible pressure. In both Figs. 1 and 1a, the pilot control valve 42 is operated when a predetermined or selected condition arises in the advance of the member 2, which condition can be either the reaching of a predetermined position as in Fig. 1, or a desired pressure on the advancing member 2 as in Fig. 1a.

The lower end of the rod 89 is provided with a head 118, Fig. 1, so that when the working member 2 has advanced to the maximum distance desired or for which the hydraulic motor 50 is designed, the head 118 will engage with the bell crank 88, rock it counter-clockwise in Fig. 1, and move the valve 29 into the intermediate position which stops the advance of the working member and holds it in that position. This is a sort of safety provision, but by making the member 118 adjustable, the press could be stopped at selected positions.

In some instances it may be desirable to control the maximum pressure that may be developed, and which pressure one may desire to maintain for a period of time, and for this purpose a pressure relief valve 119 is connected by a pipe 120 to the pipe section 33 connecting valve 36 to the high pressure chamber 6. This pipe 120 also passes beyond the valve 119 to the pump compensator 22. The valve 119 has a discharge port 121 leading to the reservoir, but this port is normally closed by the valve element 122. The valve 119 is known in the open market as a Vickers hydrocone type valve, similar to the pressure relief valve 25, one example of which is shown in U. S. Patent No. 2,043,453. With this type of relief valve there is a ball check valve 123, spring loaded to control the pressure at which the relief valve operates. Pressure in

the valve on one face of piston 124 connects through a small bleeder passage in the valve piston with a chamber at the opposite face of piston 124. The chamber at the top of the valve which carries the ball check has a larger porting than the bleeder port, and consequently when the required pressure is reached, the ball check 123 will open, relieving the pressure above the piston 124 of the valve, and hydraulic pressure on the underface of the piston will then raise it and open the port 121.

A pipe 125 is connected to the seat side of the ball check valve 123, or to the chamber at the face of the piston 124 opposite from that where the main pressure is applied, and this pipe is connected through a valve 126 to a pipe 127 which leads to a suitable pressure relief valve 128 having a discharge port 129 leading to the reservoir. The relief valve 128 is set to open at a lower pressure than that for which the ball check 123 is set to open. The valve 126 is operated into its open position by a solenoid 130 controlled manually or by any suitable automatic control, and into its closed position by spring 131. When the solenoid 130 is deenergized, spring 131 will close valve element 132 of valve 126, which disconnects the pressure relief valve 128 from the valve 119. At such time the valve 123 will unseat when the pressure for which it is set is exceeded by the pressure in the pipe 120 which corresponds to that in the high pressure, advancing chamber 6.

When the valve 123 unseats, valve piston 124 will be moved and port 121 opened. This discharges sufficient liquid moving to the advancing chamber, while the pump continues to operate, to prevent further rise in pressure in chamber 6. When solenoid 130 is energized, valve element 132 is operated out of the closed position shown in Fig. 1 to connect pipes 125 and 127 which connects the pressure relief valve 128 to the porting in valve 119 that leads to ball check valve 123. Since valve 128 is set to open at a lower pressure than that of the ball check 123, when this lower pressure is now reached, valve 128 will open and vent the port leading to the valve 123, so as to lower the pressure on that adjacent face of the piston 124 of valve 119. Valve 119 will then open port 121 at this lower pressure, and thus maintain this lower pressure while the pump operates.

Since pipe 120 is also connected to the pump compensator 22, the control of the pressure with the compensator is accomplished by an additional ball check valve 133 shown piped to the compensator by pipes 134 and 135.

It will be understood that various changes in the details, materials and arrangements of parts, which have been herein described and illustrated in order to explain the nature of the invention, may be made by those skilled in the art within the principle and scope of the invention as expressed in the appended claims.

I claim:

1. In a hydraulic motor device of the type having a double acting motor with a cylinder and a piston operating in said cylinder and advancing and retracting chambers at opposite faces of a head on said piston, the retracting chamber being disposed at the face of said head nearest the open end of the cylinder, packing around said piston adjacent the open end of said cylinder, a pump, a reservoir, a motor reversing valve, and a hydraulic operating circuit including said chambers, pump, reservoir, and valve with a connection from the output side of

said pump directly to said retracting chamber uncontrolled by said reversing valve, that improvement in the hydraulic circuit and its control which comprises an auxiliary valve in series in said connection from said pump to said retracting chamber and operable to connect said retracting chamber alternately to said reservoir and said pump separately from said reversing valve, and piston controlled means for operating said auxiliary valve to connect said retracting chamber to reservoir during a first fraction of the piston advance movement and to said pump during the remaining fraction of the piston advance movement, whereby pump pressure will be released from said retracting chamber during said first fraction of the piston advance to reduce packing friction at the open end of said cylinder opposing advance of the piston, and applied to the retracting chamber solely during the final fraction of the piston advance, when high pressures are exerted on said head and balancing of the pressures on any packing on said head is desired.

2. In a hydraulic motor device of the type having a double acting motor with packing between the cylinder and the piston adjacent the zone where the piston leaves the cylinder, a pump, a reservoir, a main control valve and a hydraulic circuit connecting said pump to the advancing and retracting chambers of said motor, with said control valve in the connection between the pump and said advancing chamber, that improvement which comprises a portion of said hydraulic circuit having a direct connection from said pump to said retracting chamber separately from said reversing valve, an auxiliary valve in said connection to said retracting chamber operable to connect said retracting chamber alternately to said pump and to said reservoir, pilot means responsive to the pressure of fluid delivered by the pump to the advancing chamber for operating said auxiliary valve into a position to connect said reservoir to said retracting chamber, further pilot means for operating said auxiliary valve into the position in which it connects said retracting chamber to said pump and having greater pressure force on said auxiliary valve than said first pilot means, and means controlled by the ram travel for rendering said further pilot means effective and ineffective.

3. In a hydraulic motor device of the type having a double acting hydraulic motor with a ram extending from the cylinder and a retracting chamber at the end of the cylinder from which the ram extends, and with packing between the ram and cylinder adjacent said end of said cylinder, a pump, a reservoir, a connection from the pump to the advancing chamber of the motor with a control valve therein, and another connection from the pump directly to said retracting chamber and by-passing said control valve, that improvement which comprises an auxiliary valve in said another connection and operable to connect said retracting chamber alternately to said pump and to said reservoir, irrespective of the position of said control valve, pilot means responsive to the pressure of the fluid delivered by the control valve to the advancing chamber for operating said auxiliary valve into a position to connect the retracting chamber to said reservoir, further pilot means for moving said auxiliary valve into a position to connect said retracting chamber to said pump and having greater moving power on the auxiliary valve than said first pilot means, a connection from said pump to said further pilot means, a valve in said last connec-

tion and operated by said ram when in a selected zone of its travel for connecting the pump to said further pilot means.

4. In a hydraulic motor device of the type having a working member having a piston head, a cylinder into which the head carrying end of said working member extends, packing at the end zone of said cylinder where said member enters, a rapid traverse chamber for acting on said member at one side of said head to advance it by pressure, a high pressure chamber at the same side of said head for also acting on said member to advance it, a retracting chamber at the opposite side of the head, a pump, a reservoir, a connection from said pump to said rapid traverse chamber, a control valve in said connection, a branch from said control valve to said high pressure chamber, a valve in said branch connection, and a connection from said pump to said retracting chamber separately from said control valve, that improvement which comprises an auxiliary valve in said last connection to said retracting chamber and operable to connect said retracting chamber alternately to said pump and to said reservoir uncontrolled by said control valve, means responsive to the pressure of the fluid delivered by said control valve to said rapid traverse chamber for operating said auxiliary valve to connect the retracting chamber to said reservoir, further means for shifting said auxiliary valve to connect said retracting chamber to said pump, and more powerful in its shifting action than said pressure responsive means, and means for selectively controlling said further means, whereby said retracting chamber may be connected to the reservoir to lessen packing friction during any desired portion of the advance movement of said member, and connected to said pump only while very high pressures on said head are being exerted.

5. In a hydraulic motor device of the type having advancing and retracting chambers, a working member movable in response to relative pressures in said chambers, a pump, a reservoir, connections from the pump to said reservoir and to each chamber, and a control valve in the connection from the pump to the advancing chamber leaving the connection to the retracting chamber uncontrolled thereby, that improvement which comprises an auxiliary valve in the connection from said pump to said retracting chamber and operable between two positions to connect said retracting chamber alternately to said pump and to said reservoir but yieldingly urged into a position to connect said retracting chamber to said reservoir, means responsive to the travel of said working member and rendered effective when said member reaches a selected intermediate position in its advance for operating said auxiliary valve to connect said pump to said retracting chamber for the remainder of the advance.

6. In a hydraulic motor device of the type having advancing and retracting chambers, a pump, a reservoir, a connection from the pump to said reservoir and to each chamber, and a control valve in the connection from the pump to the advancing chamber leaving the connection to the retracting chamber uncontrolled thereby, that improvement which comprises an auxiliary valve in the connection from said pump to said retracting chamber and operable to connect said retracting chamber alternately to said pump and to said reservoir, means responsive to the pressure of fluid delivered by said control valve

to the advancing chamber for moving said auxiliary valve into a position to connect said retracting chamber to the reservoir while pressure is applied to the advancing chamber, and additional means for operating said auxiliary valve against the action of said pressure responsive means into a position in which it connects the retracting chamber to said pump, whereby the full pressure of the pump may be applied to said retracting chamber during a desired portion of the advance movement of said motor.

7. In a hydraulic motor device of the type having advancing and retracting chambers, a pump, a reservoir, a connection from the pump to said reservoir and to each chamber, and a control valve in the connection from the pump to the advancing chamber leaving the connection to the retracting chamber uncontrolled thereby, that improvement which comprises an auxiliary valve in the connection from said pump to said retracting chamber and operable to connect said retracting chamber alternately to said pump and to said reservoir, means responsive to the pressure of fluid delivered by said control valve to the advancing chamber for moving said auxiliary valve into a position to connect said retracting chamber to the reservoir while pressure is applied to the advancing chamber, and platen controlled means for operating said auxiliary valve, against the action of said fluid pressure responsive means, into a position to connect said retracting chamber directly to said pump during a final portion of the advance of said motor.

8. In a hydraulic motor device of the type having a working member having a piston head, a cylinder into which the head carrying end of said working member extends, packing at the end zone of said cylinder where said member enters, a rapid traverse chamber for acting on said member at one side of said head to advance it by pressure, a high pressure chamber at the same side of said head for also acting on said member to advance it, a retracting chamber at the opposite side of said head, a pump, a reservoir, a connection from said pump to said rapid traverse chamber, a control valve in said connection, a branch from said control valve to said high pressure chamber, a valve in said branch connection, and a connection from said pump to said retracting chamber separately from said control valve, that improvement which comprises an auxiliary valve in said last connection to said retracting chamber and operable to connect said retracting chamber alternately to said pump and to said reservoir uncontrolled by said control valve, means responsive to the pressure of the fluid delivered by said control valve to said rapid traverse chamber for operating said auxiliary valve to connect the retracting chamber to said reservoir, and further means responsive to the operation of said working member for shifting said auxiliary valve against the action of said pressure responsive means to connect said retracting chamber to said pump and for concurrently operating said branch valve to connect said control valve directly to said high pressure chamber, whereby at a selected position in the advance of said working member the pump pressure may be applied to the retracting chamber during the advance of the working member, and the pump pressure also applied to the high pressure chamber concurrently with the application of pump pressure to the retracting chamber in the advance of the working member.

9. In a hydraulic motor device of the type hav-

ing a working member having a piston head, a cylinder into which the head carrying end of said working member extends, packing at the end zone of said cylinder where said member enters, a rapid traverse chamber for acting on said member at one side of said head to advance it by pressure, a high pressure chamber at the same side of said head for also acting on said member to advance it, a retracting chamber at the outer side of said head, a pump, a reservoir, a connection from said pump to said rapid traverse chamber, a control valve in said connection, a branch from said control valve to said high pressure chamber, a valve in said branch connection, and a connection from said pump to said retracting chamber separately from said control valve, that improvement which comprises an auxiliary valve in said last connection to said retracting chamber and operable to connect said retracting chamber alternately to said pump and to said reservoir uncontrolled by said control valve, means responsive to the pressure of the fluid delivered by said control valve to said rapid traverse chamber for operating said auxiliary valve to connect the retracting chamber to said reservoir, pilot means for operating said auxiliary valve against the action of said pressure responsive means to connect said retracting chamber to said pump, a connection from the pump to said pilot means and having a pilot control valve therein, means controlled by the travel of said working member for operating said pilot control valve into a position to cause said pilot means to connect the retracting chamber to the pump after the working member passes a selected position in its advance, and means also rendered effective by the same movement of said pilot control valve for operating said branch valve to connect said main control valve to said high pressure chamber concurrently with the operation of said auxiliary valve into a position to connect the retracting chamber to the pump.

10. In a hydraulic motor device of the type having a double acting motor with a working member, advancing and retracting chambers for moving said member, a pump, a connection from the pump to the advancing chamber and having a main control valve solely in that connection, and a reservoir with connections from said main control valve and said pump to the reservoir, that improvement which comprises an auxiliary valve solely in the connection from the pump to the retracting chamber, separately from the main control valve, and operable to connect said retracting chamber alternately to said pump and to said reservoir, a pilot device operated by the fluid under pressure passed by said main valve to the advancing chamber, for operating the auxiliary valve to disconnect the pump from the retracting chamber, and a more powerful pilot device controlled by an advancing condition of the motor for overcoming the first pilot device and moving the auxiliary valve to reconnect the pump to the retracting chamber for the balance of the advance of the motor whereby during an advance of said motor the retracting chamber can be connected to the reservoir to reduce the packing friction on the working member of the motor during the advance movement until any desired intermediate condition in the advance of the working member of the motor, and then connected to said pump during further advance of the working member.

11. In a hydraulic motor device of the type having a double acting motor with a working

member, advancing and retracting chambers for moving said member, a pump, a connection from the pump to the retracting chamber, a connection from the pump to the advancing chamber and having a main control valve solely in that connection, and a reservoir with connections from said main control valve and said pump to the reservoir, that improvement which comprises an auxiliary valve solely in the connection from the pump to the retracting chamber, uncontrolled by the main control valve, pilot means responsive to the pressure of the fluid delivered by the main control valve to the advancing chamber for operating said auxiliary valve into a position to connect the retracting chamber to the reservoir, and control means rendered effective by said working member at a selected position in its advance for operating said auxiliary valve against the action of said pilot means into the position in which it connects the retracting chamber directly to the pump during further advance movement.

12. In a hydraulic motor device of the type having a double acting motor with a working member, advancing and retracting chambers for moving said member, a pump, a connection from the pump to the retracting chamber, a connection from the pump to the advancing chamber and having a main control valve solely in that connection, and a reservoir with connections from said main control valve and said pump to the reservoir, that improvement which comprises an auxiliary valve solely in the connection from the pump to the retracting chamber, uncontrolled by the main control valve, pilot means responsive to the pressure of the fluid delivered by the main control valve to the advancing chamber for operating said auxiliary valve into a position to connect the retracting chamber to the reservoir, further pilot means operable on said auxiliary valve to shift it into a position to connect said retracting chamber directly to said pump, a connection from said pump to said further pilot means uncontrolled by said main control valve, a pilot control valve in said last connection, means operated by the motor when a predetermined operating condition has been reached in its advance for moving said pilot control valve into a position to connect said pump to said further pilot means, whereby the motor automatically causes the connection of said pump directly to said retracting chamber at any selected condition in the advance movement of said motor, whereby the packing friction on the motor may be reduced by a release of the pressure in the retracting chamber until the pressure in the retracting chamber serves a useful purpose.

13. A hydraulic motor and controls comprising a cylinder, a piston having a head in and fitting said cylinder and a shank extending from the open end of said cylinder, packing between the piston shank and the cylinder adjacent to the open end of the cylinder, whereby the chamber at the inner end of the cylinder closed by said head will constitute an advancing chamber and the space in the cylinder at the opposite side of said head and around said shank to said packing, will constitute a retracting chamber, a pump, a reservoir, a pilot operated prefill check valve connecting said advancing chamber to the reservoir, a connection from the intake side of said pump to said reservoir, another connection from the output side of said pump to said advancing chamber, a main control valve in said last connection, a connection from the output side of

said pump to said retracting chamber uncontrolled by said main control valve, the valve element of said main control valve having an operating stem extending therefrom, means yieldingly urging said valve stem into a position to cause the valve element to connect the advancing chamber to the reservoir and disconnect it from the pump, and connect the pump to the pilot chamber of said prefill valve to urge the prefill valve to open position, means for moving said valve stem against the action of said yielding means into a position in which the valve element is placed in a position in which the pump is connected to the advancing chamber and disconnected from the pilot chamber, means rendered effective by the piston at a selected position in its retraction for moving the valve stem against the action of said resilient means into an intermediate position in which the valve element disconnects the pump from the advancing chamber, and closes the connection from the control valve to the advancing chamber, connects said pump to said reservoir, and uncovers the connection to said pilot chamber, and an auxiliary valve in the connection from said pump to said retracting chamber and having a valve member operable to connect said retracting chamber alternately to the reservoir and the pump and uncontrolled by said main control valve, means continuously responsive to the pressure of fluid moving into said advancing chamber for operating said auxiliary valve to connect said retracting chamber to the reservoir and disconnect it from said pump, and means controlled by said piston and rendered effective automatically at an intermediate point in its advance to operate said auxiliary valve by the pump pressure to overcome said continuously responsive means and reconnect the pump to said retracting chamber and disconnect the latter from said reservoir throughout the remainder of the advance of said piston and until the piston reaches the same intermediate position in its retracting movement, whereby said retracting chamber may be connected to said reservoir during a desired portion of an advance of said piston to relieve the packing friction on the piston adjacent the open end of said cylinder, and connected to the pump only during the part of the advance movement where one desires to prevent danger of jumping of the piston under high pressure or when balancing is desired on the packing between the head of the piston and the cylinder.

14. A hydraulic motor and controls comprising a cylinder, a piston having a head in and fitting said cylinder, and a shank extending from the open end of said cylinder, packing between the piston shank and the cylinder adjacent to the open end of the cylinder, whereby the chamber at the inner end of the cylinder closed by said head will constitute an advancing chamber and the space in the cylinder at the opposite side of said head and around said shank to said packing, will constitute a retracting chamber, a pump, a reservoir, a pilot operated prefill check valve connecting said advancing chamber to the reservoir, a connection from the intake side of said pump to said reservoir, another connection from the output side of said pump to said advancing chamber, a main control valve in said last connection, a connection from the output side of said pump to said retracting chamber uncontrolled by said main control valve, the valve element of said main control valve having an operating stem extending therefrom, means yieldingly urging said valve stem into a position to cause the valve element to connect the advancing chamber to the reservoir and disconnect it from the pump, and connect the pump to the pilot chamber of said prefill valve to urge the prefill valve to open position, means for moving said valve stem against the action of said yielding means into a position in which the valve element is placed in a position in which the pump is connected to the advancing chamber and disconnected from the pilot chamber, means rendered effective by the piston at a selected position in its retraction for moving the valve stem against the action of said resilient means into an intermediate position in which the valve element disconnects the pump from the advancing chamber, and closes the connection from the control valve

said resilient means into an intermediate position in which the valve element disconnects the pump from the advancing chamber, and closes the connection from the control valve to the advancing chamber, connects said pump to said reservoir, and uncovers the connection to said pilot chamber, and an auxiliary valve in the connection from said pump to said retracting chamber and having a valve member operable to connect said retracting chamber alternately to the reservoir and the pump and uncontrolled by said main control valve, means continuously responsive to the pressure of fluid moving into said advancing chamber for operating said auxiliary valve to connect said retracting chamber to the reservoir and disconnect it from said pump, and means controlled by said piston and rendered effective automatically at an intermediate point in its advance to operate said auxiliary valve by the pump pressure to overcome said continuously responsive means and reconnect the pump to said retracting chamber and disconnect the latter from said reservoir throughout the remainder of the advance of said piston and until the piston reaches the same intermediate position in its retracting movement, whereby said retracting chamber may be connected to said reservoir during a desired portion of an advance of said piston to relieve the packing friction on the piston adjacent the open end of said cylinder, and connected to the pump only during the part of the advance movement where one desires to prevent danger of jumping of the piston under high pressure or when balancing is desired on the packing between the head of the piston and the cylinder.

15. A hydraulic motor and controls comprising a cylinder, a piston having a head in and fitting said cylinder and a shank extending from the open end of said cylinder, packing between the piston shank and the cylinder adjacent to the open end of the cylinder, whereby the chamber at the inner end of the cylinder closed by said head will constitute an advancing chamber and the space in the cylinder at the opposite side of said head and around said shank to said packing, will constitute a retracting chamber, a pump, a reservoir, a pilot operated prefill check valve connecting said advancing chamber to the reservoir, a connection from the intake side of said pump to said reservoir, another connection from the output side of said pump to said advancing chamber, a main control valve in said last connection, a connection from the output side of said pump to said retracting chamber uncontrolled by said main control valve, the valve element of said main control valve having an operating stem extending therefrom, means yieldingly urging said valve stem into a position to cause the valve element to connect the advancing chamber to the reservoir and disconnect it from the pump, and connect the pump to the pilot chamber of said prefill valve to urge the prefill valve to open position, means for moving said valve stem against the action of said yielding means into a position in which the valve element is placed in a position in which the pump is connected to the advancing chamber and disconnected from the pilot chamber, means rendered effective by the piston at a selected position in its retraction for moving the valve stem against the action of said resilient means into an intermediate position in which the valve element disconnects the pump from the advancing chamber, and closes the connection from the control valve

to the advancing chamber, connects said pump to said reservoir, and uncovers the connection to said pilot chamber, an auxiliary valve in the connection from said pump to said retracting chamber and operable to connect said retracting chamber alternately to the reservoir and the pump and uncontrolled by said main control valve, whereby said retracting chamber may be connected to said reservoir during a desired portion of an advance of said piston to relieve the packing friction on the piston adjacent the open end of said cylinder, and connected to the pump only during the part of the advance movement where one desires to prevent danger of jumping of the piston under high pressure or when balancing is desired on the packing between the head of the piston and the cylinder, pilot means responsive to the pressure of fluid delivered by said control valve to the advancing chamber for automatically moving said auxiliary valve into a position to connect the retracting chamber to the reservoir during an initial advance of said piston, further pilot means operated by pressure from said pump for moving said auxiliary valve against the action of said first pilot means into a position to connect said retracting chamber directly to the pump, a pilot control valve for connecting said further pilot means alternately to the reservoir and to said pump, and means for operating said pilot control valve in response to a predetermined operating condition of said piston.

16. A hydraulic motor and controls comprising a cylinder, a piston having a head in and fitting said cylinder and a shank extending from the open end of said cylinder, packing between the piston shank and the cylinder adjacent to the open end of the cylinder, whereby the chamber at the inner end of the cylinder closed by said head will constitute an advancing chamber and the space in the cylinder at the opposite side of said head and around said shank to said packing, will constitute a retracting chamber, a pump, a reservoir, a pilot operated prefill check valve connecting said advancing chamber to the reservoir, a connection from the intake side of said pump to said reservoir, another connection from the output side of said pump to said advancing chamber, a main control valve in said last connection, a connection from the output side of said pump to said retracting chamber uncontrolled by said main control valve, the valve element of said main control valve having an operating stem extending therefrom, means yieldingly urging said valve stem into a position to cause the valve element to connect the advancing chamber to the reservoir and disconnect it from the pump, and connect the pump to the pilot chamber of said prefill valve to urge the prefill valve to open position, means for moving said valve stem against the action of said yielding means into a position in which the valve element is placed in a position in which the pump is connected to the advancing chamber and disconnected from the pilot chamber, means rendered effective by the piston at a selected position in its retraction for moving the valve stem against the action of said resilient means into an intermediate position in which the valve element disconnects the pump from the advancing chamber, and closes the connection from the control valve to the advancing chamber, connects said pump to said reservoir, and uncovers the connection to said pilot chamber, an auxiliary valve in the connection from said pump to said retract-

ing chamber and operable to connect said retracting chamber alternately to the reservoir and the pump and uncontrolled by said main control valve, whereby said retracting chamber may be connected to said reservoir during a desired portion of an advance of said piston to relieve the packing friction on the piston adjacent the open end of said cylinder, and connected to the pump only during the part of the advance movement where one desires to prevent danger of jumping of the piston under high pressure or when balancing is desired on the packing between the head of the piston and the cylinder, pilot means responsive to the pressure of fluid delivered by said control valve to the advancing chamber for automatically moving said auxiliary valve into a position to connect the retracting chamber to the reservoir during an initial advance of said piston, further pilot means operated by pressure from said pump for moving said auxiliary valve against the action of said first pilot means into a position to connect said retracting chamber directly to the pump, a pilot control valve for connecting said further pilot means alternately to the reservoir and to said pump, and means operated by the piston during its advance for operating said pilot control valve to cause movement of said auxiliary valve into a position to connect the retracting chamber to the pump during any portion of the final advance movement of said piston.

17. In a hydraulic motor device of the type having a double acting motor with a working member, advancing and retracting chambers for moving said member, a pump, a reservoir connected to the intake side of the pump, a connection from the pump to the retracting chamber, a connection from the pump to the advancing chamber and having a main control valve solely in that connection, that improvement which comprises an auxiliary valve in the connection from the pump to the retracting chamber uncontrolled by the main valve, and operable to connect said retracting chamber alternately to said pump and to said reservoir, means responsive to the fluid pressure in the connection from said main control valve to the advancing chamber for moving said auxiliary valve into a position to connect said retracting chamber to said reservoir, and means for automatically operating said auxiliary valve against the action of said pressure responsive means into a position to connect said retracting chamber to said pump in response to a predetermined operating condition of said motor during its advance.
